UNITED STATES PATENT OFFICE

THOMAS W. McCREARY, OF MONACA, PENNSYLVANIA, ASSIGNOR TO THE PHOENIX
GLASS COMPANY, OF MONACA, PENNSYLVANIA, A CORPORATION OF WEST
VIRGINIA

DESIGN FOR AN AQUARIUM BOWL

Application filed May 12, 1931. Serial No. 39,819. Term of patent 7 years.

To all whom it may concern:

Be it known that I, THOMAS W. McCREARY, a citizen of the United States, residing at Monaca, in the county of Beaver, State of Pennsylvania, have invented a new, original, and ornamental Design for an Aquarium Bowl, of which the following is a specification, reference being had to the accompanying drawings, forming a part thereof.

Figure 1 is a plan view showing my new design, Fig. 2 is a vertical section thereof, and Fig. 3 is a perspective view, on a reduced scale.

I claim:

The ornamental design for an aquarium bowl, as shown.

THOMAS W. McCREARY.
